No 22,519. Patented Jan 4, 1859.

UNITED STATES PATENT OFFICE

WM. H. STUBBE, OF BOSTON, MASSACHUSETTS.

LITHOGRAPHIC-PRINTING PRESS.

Specification of Letters Patent No. 22,519, dated January 4, 1859.

To all whom it may concern:

Be it known that I, WM. H. STUBBE, of Boston, in the county of Suffolk and State of Massachusetts, have invented a new and Improved Lithographic-Printing Press, of which the following is a full, clear, and exact description, reference being had to the accompanying drawings, making part of this specification, in which—

10 Figure 1, is a plan of my machine. Fig. 2, a vertical section through the same. Figs. 3, 4 and 5, details to be referred to hereafter.

15 My invention has for its object to perform the operations of moistening and inking the stone, and of taking the impression upon the paper all by machinery and my invention consists in an automatic machine for the purpose of effecting the same which I will now proceed particularly to describe.

20 The lithographic stone X^3 is secured to the top of the carriage A and is raised to the required height by the introduction of boards or paper beneath it in the customary manner. The carriage is vibrated back and forth as follows—Six flanged wheels B, the axles T, T', T'', of which are connected by the perches R, run upon rails C, and are traversed back and forth by the connecting rod D, and crank E, upon the driving shaft 25 F. Upon the center of the shaft T' is a gear G, which engages with a stationary rack H, and a corresponding rack K, upon the bottom of the traveling carriage A. To each end of this carriage are secured timbers W, which rest upon the treads of the flanged wheels B, and thus by means of the gear G, and racks H and K, the carriage is traversed both forward and back a distance equal to double that moved by the wheels

30 B. As the carriage with its stone thus traverses back and forth the operations of “wiping” (moistening) inking, and printing are performed in succession as follows—The water for moistening the stone is contained 35 in the trough I, from which it drops through the funnel a, into a receiver b, there being a funnel and receiver upon each of the ends of the shaft of the moistening roller L; the shaft c, of this roll is made of copper tubing

40 into which the water is admitted from the receivers b; this tube c, is pierced with holes to permit the water to flow through and saturate a covering of sponge d, which surrounds it—outside the sponge is a covering 45 f of flannel and surrounding the whole are one or more thicknesses e, of cotton or linen

cloth. As the carriage moves in the direction of its arrow the surface of the stone bears against the moistening roll and the stone is wiped as required the roll being 50 revolved by the contact of the stone.

For the purpose of taking up the superfluous water from the moistening roll L, an absorber M, of sponge or other suitable material is placed immediately to the rear of 55 it, and is raised and lowered with it. When the carriage moves in the direction of its arrow the moistener and absorber are allowed to drop upon the surface of the stone, but when the carriage returns in the opposite direction after the stone has been inked the moistener and absorber are raised clear 60 of the stone by means not shown in the drawings, they are seen elevated in Fig. 2.

The absorber M in addition to taking up 65 the superfluous water of the moistening roll serves also to “wipe” the advance and rear edges of the stone for the purpose of preventing them from taking ink as they pass the ink rolls. At Z, Fig. 2 is seen one of 70 two wipers which are saturated with water and serve to moisten the side edges of the stone and in a similar manner prevent them from taking ink, they are carried by a transverse rod upon which they may be adjusted 75 in position to suit stones of various widths. As the carriage still moves in the direction of its arrow Fig. 2, the stone is inked as follows—The ink is contained within the trough N from which it is transferred by 80 the rolls S, and O, to the vibrating distributing cylinder Q, by which the ink rolls R are served, and in contact with these latter the stone X^3 on the carriage A passes twice, once as it advances and again on its return—85 the roll S, is driven by a cord Y, from the main shaft F. P is a shaft on which the arms that carry the roll O, are hung. I will now describe the manner in which the paper is fed to the stone and passed beneath 90 the scraper for the purpose of producing the impression.

The paper is introduced by the attendant into nippers g, which are operated as follows: U and V, are stationary heads secured 95 to a fixed shaft X, these heads do not revolve, they carry a number of rollers m, which together form a cylinder that supports a revolving tympan i of sheet metal, which together with the nippers g, are secured to a sheet of stouter metal B² which 100 extends the whole length of the cylinder of 110

rollers, as seen in Fig. 1. Upon each end of the shaft X, is a gear C², which is revolved by racks D² upon the carriage A, one of the racks being seen in Fig. 2—to 5 each of these wheels is connected one end of the metal plate B² and thus as the gears C² are revolved the plate is carried around the drum and with it the tympan and nippers. This revolution of the gears, plate 10 and tympan takes place only in one direction, while the carriage is running back after the ink has been applied to the stone. When the carriage advances after an impression has been taken the racks D² are dis- 15 engaged from the gears C² so that the latter remain stationary in the following manner. A portion of the teeth of the gears C² are cut away at 10 Fig. 2, so that on the arrival of the nippers g into position to receive a 20 sheet of paper the toothless portion of the gears shall be opposite to the racks D² and the parts remain in this position until after the stone has again been inked and returns to give another impression. The motions 25 of the gears C² during this part of the operation are governed as follows: One of the gears C², carries upon its outside face and directly over the part where the teeth are cut away a pin a², which at certain times 30 enters a notch in the end of a lever E², pivoted at b² to the framework. The position of this lever is governed by two corresponding cams f² seen detached and in elevation in Fig. 4, and which are set counter 35 to each other upon the shaft F, these cams are partly concentric and partly irregular so that motion is imparted through the rod F² to the lever E², as follows: As the gear C², revolves the lever E² is thrown by its cams 40 f², into the position seen dotted in Fig. 3, and the pin a², falls into the notch in its extremity—the cams f², are so shaped that the lever E², follows the motions of the pin until it arrives into the position seen in 45 black in Fig. 3, when the toothless portion of gears arriving opposite to the rack the gears remain stationary while the carriage completes its motions. At the same time the cams f² being both concentric the lever E², 50 is held stationary and the gears with the tympan are held for the time immovable and before they can be again set in motion the gears must be revolved sufficiently to engage them with the racks—this is effected 55 by the cams f² which now move the lever E², in the direction of its arrow into the position shown in red Fig. 3, until the gears and racks once more engage, when the former are caused to make another revolution 60 as before.

It now remains to be shown how the nippers g, are opened and closed. Their movable jaws are attached to a rod i² which is connected by a jointed arm g² with a pin d² 65 that passes through a slot in one of the

gears C² and rests upon the periphery of a cam G² Fig. 3 that is loose upon the stationary shaft X, this cam is concentric and of such a diameter from 1, to 2, that the nippers are allowed to remain closed, but 70 on the pin ascending the eccentric portion 2, the nippers are opened and remain so until just before the gears C² and tympan commence again to move, when the cam G², receives a motion in the direction of its arrow 75 sufficient to allow the pin d² to be drawn down upon the cam at 1, by a spring 15, Fig. 5, whereby the nippers are closed, ready to make another revolution. This motion of the cam G², to close the nippers is effected 80 as follows: H² is an arm attached to the cam and connected by the link I² to a bell crank lever K² pivoted at n², to the other arm of the lever K², is attached the pendant bar L² which is raised and lowered for the purpose of imparting the required movements 85 to the cam G² by a switch M², upon the side of the carriage. A pin e² upon the end of the bar L² passing out of the switch beneath the spring h² and thus moving the cam and 90 closing the nippers and on the arrival of the carriage at the other end of its traverse the pin e² enters the switch at k², and again moves the cam into a position ready to close the nippers when it is again moved as before 95 explained.

In Fig. 1 are seen in plan two stops 7, which arrest the sheet of paper at the proper point as it is fed by the attendant, to be grasped by the nippers—one of these 100 stops is seen in elevation in Fig. 2, they are dropped in contact with the tympan when a sheet is to be fed to the nippers, and are raised clear of it before it commences to revolve as follows: Attached to the vibrating shaft of the bell crank lever K² (Fig. 3) is an arm N² on the end of which is a pin that plays in a slot p, in the arm O², fixed upon the shaft 8, to which the stops are attached, and thus whenever 105 the pin e² upon the bar L² drops out of the switch at h² the stops are raised and when this pin enters the switch at k² the stops 110 7 drop upon the tympan.

It now remains to explain the manner in 115 which the scraper is caused to descend upon the tympan and force the paper down upon the stone to take the impression.

It has already been explained that the rollers m remain stationary except so far 120 as they may be revolved upon their own axes by the passage of the metallic tympan around them. Between the two lower rolls of the set is a timber or block R² which carries the scraper t² this block is held up 125 so that the scraper shall not come in contact with the tympan by springs which hang upon the shaft X (one of which is seen at p² Fig. 2) it is depressed however for the purpose of forcing the scraper down 130

upon the stone by means of cams S^2 attached to the gears C^2 and revolving therewith, one of these cams is shown in red in Fig. 2.

5 w are cords by which the printed sheet is led out of the machine in the customary manner, and U^2 is a table for holding the unprinted paper.

10 The cylinder of rollers and its shaft X , are hung in bearings which are connected with the framework by springs 17, shown in red Fig. 3, that the stone may not be broken by the too great rigidity of the scraper or the parts which actuate it.

15 I have spoken of the tympan i as made of sheet metal, leather may however be used instead.

20 Operation: The parts being in the position represented in Fig. 1, and the carriage moving in the direction of its arrow (Fig. 2) the stone passes first under the "wiper" L , and is then inked as described, while this is going on the toothless portion 10 of the gears C^2 being opposite to the racks D^2 the 25 tympan and nippers remain stationary, the nippers being retained open by the pin d^2 resting upon the portion of the cam G^2 of largest diameter, and the stops rest upon the tympan, occasion is taken of this state of 30 things to introduce a sheet of paper to the nippers and the next instant as the carriage proceeds in the same direction the pin upon the bar L^2 passes out of the switch M^2

upon the carriage the nippers are closed by the sudden motion of the cams G^2 and 35 the stops 7, are raised to permit the revolution of the tympan. The cams f^2 upon the shaft F now move the lever E^2 in the direction of its arrow and engage the gears C^2 with the racks D^2 and as the carriage 40 now commences to return the gears are revolved and the nippers and tympan are carried around whereby the paper is brought in contact with the stone. The cams S^2 now 45 force down the scraper upon the tympan which presses the paper down upon the stone and the impression is taken.

What I claim as my invention and desire to secure by Letters Patent is—

1. I claim the cylinder of rollers m in 50 combination with a revolving tympan and scraper operating as set forth for the purpose described.

2. I claim the method of interrupting the motion of the gears C^2 and of again engaging them with the rack by means of the cams f^2 lever E^2 and pin d^2 operating in 55 the manner set forth.

3. I claim hanging the parts which operate the scraper on springs 17 in the manner 60 substantially as specified.
